COMBINED HAT AND COAT RACK

Raymond A. Magnuson, Hinsdale, Ill., assignor to Vogel-Peterson Co., Elmhurst, Ill., a corporation of Illinois

Filed Sept. 10, 1965, Ser. No. 86,934

Term of patent 14 years

(Cl. D33—8)

FIG. 2 is a front elevational view of the rack of FIGURE 1.

FIG. 3 is an end elevational view of the rack of the preceding figures.

I claim:

The ornamental design for a combined hat and coat rack, as shown.
